UNITED STATES PATENT OFFICE.

JEFFERSON DAVIS GODDARD, OF KANSAS CITY, MISSOURI.

DESIGN FOR A DISPLAY-STAND.

SPECIFICATION forming part of Design No. 24,702, dated September 24, 1895.

Application filed August 24, 1895. Serial No. 560,439. Term of patent 14 years.

To all whom it may concern:

Be it known that I, JEFFERSON DAVIS GODDARD, of Kansas City, in the county of Jackson and State of Missouri, have invented and 5 produced a new and original Design for a Display-Stand, of which the following is a specification.

Reference is to be had to the accompanying drawing, which shows a perspective view of a 10 stand embodying my new design.

The leading feature of my design consists in the body of the stand having the central portion of its top and bottom in a higher plane than the side portions of said top and bottom.

Minor features of the design consist in the 15 vertical partition in the body, the round molded base, with a cylindrical standard rising therefrom to the body, and the staff rising from the top of the body and having a pennant thereon. 20

I claim—

The design for a display stand herein shown and described.

JEFFERSON DAVIS GODDARD.
